United States Patent Office

Des. 207,618
Patented May 9, 1967

207,618

PIPE HOLDER OR SIMILAR ARTICLE

Orland Perry, 309 Birmingham Ave.,
Pittsburgh, Pa. 15202

Filed June 21, 1966, Ser. No. 2,763

Term of patent 7 years

(Cl. D85—8)

Fig.2

Fig.3

FIG. 1 is a perspective view of a pipe holder showing my new design, with a stand therefor shown fragmentarily in broken lines for illustrative purposes;

I claim:

The ornamental design for a pipe holder or similar article, substantially as shown and described.
